UNITED STATES PATENT OFFICE.

CHARLES SCHAEFFER, OF PARIS, FRANCE, ASSIGNOR TO SOCIÉTÉ DES ANCIENS
ETABLISSEMENTS PANHARD ET LEVASSOR, OF PARIS, FRANCE.

CYLINDER HEAD FOR INTERNAL-COMBUSTION ENGINES.

Application filed July 18, 1922. Serial No. 575,903.

To all whom it may concern:

Be it known that I, CHARLES SCHAEFFER, a citizen of the Republic of France, and residing at Paris (Seine Department), No. 19 5 Avenue d'Ivry, in the Republic of France, have invented certain new and useful Improvements in Cylinder Heads for Internal-Combustion Engines, of which the following is a specification.

10 This invention relates to the manufacture of cylinder heads for internal combustion engines of the valveless type. In known devices the cylinder heads of said engines, which comprise an external portion of cylindrical shape and an internal portion forming a combustion chamber and seat for the spark plug, are made in a single cast piece.

This method of manufacture has serious drawbacks. The porous character generally 20 possessed by the cast pieces will cause a considerable waste in the manufacture; the walls have an irregular thickness, leading to the moulding of greater thicknesses than are absolutely necessary, whence the relatively great weight of the material which is prejudicial to economy in the manufacture.

In the present invention, the cylinder heads are on the contrary made in two or more pieces, and by reason of this separation, all parts of the cylinder head can be 30 treated by machine in a ready and exact manner, so that they will have the maximum lightness and will be perfectly balanced, besides being capable of withstanding all required stresses in the best conditions.

In this event the various pieces can be 40 made of steel or bronze or like alloy having equivalent properties, and can be assembled by screwing, hard soldering or welding or by like means.

For this purpose, the circular joint between the two pieces forming the cylinder head, instead of being made upon a diameter which is substantially equal to the periphery of said cylinder head, is made upon a 45 reduced diameter around the socket of the spark plug, and in this manner the connection between the two pieces and the soldering substance which consolidates the same 50 will be obliged to support a much smaller stress.

Various forms of construction of a cylinder head according to this invention are shown in vertical section in Figs. 1, 2 and 3

of the accompanying drawing by way of example.

The cylinder head, Fig. 1, is composed of the outer member 1 and the inner member 2, whereof the first having a cylindrical shape is provided at the top with a flange 3 serving to secure it on the cylinder; it has at the exterior a set of flanges 4 adapted to receive packing members and in the interior a circular shoulder 5. The inner member 2 is provided with a portion which spreads out at the bottom with an edge 6 co-operating with the shoulder 5, as well as a portion which spreads out at the top, the junction of these two parts forming a seat 7 intended to receive a spark plug. These two pieces are connected by a welded joint at 8. By reason of the shoulder 5, the violent shocks due to the combustion of gas are directly transmitted from member 2 to member 1, so that the joint 8 suffers no excessive strain.

In Figs. 2 and 3, the outer part 1 of the cylinder head is integral with a conical part 9 serving as a support for the inner member 2; said conical part is provided with a groove 10 wherein is disposed a collar 11 ending the member 2. When mounting the device, said collar is cylindrical as shown in Fig. 3, and it is then changed in shape by hammering or by seating so as to extend into the groove 10, Fig. 2. All the cavities are then filled up with solder 12 which comes flush with the inner walls of the cone 9.

In practice, the collar 11 is preferably overturned by seating, and then is welled as above stated, but without departing from the invention, the two pieces could be secured together by screwing or by like means with or without soldering, provided the proper tightness is secured; as observed, each of the members may be readily treated by machine in the interior and at the exterior in an exact and perfect manner.

Claims:

1. Cylinder head for internal combustion engine composed of a peripheral portion and a central portion which are distinct from each other, said peripheral portion having an external cylinder part and a disk-shaped internal part whereof the central aperture is relatively small, the internal edge of said aperture having a groove formed therein and the central portion of the cylinder head having an annular extension fitting into said

central aperture, the edge of said extension being outwardly flared and engaging in said groove.

2. The structure of claim 3 having the 5 flared portion of the central portion secured in the groove of the peripheral portion by solder.

3. A cylinder head for internal combustion engines composed of an outer part and 10 of a central part which are distinct the one from the other, worked separately and then soldered together, the outer part having an internal circular groove and the inner part having a flange adapted to be forced into 15 the said groove.

4. A cylinder head for internal combus-

tion engines composed of an outer peripheral part and a central inner part which are distinct from each other, said inner part having a cup-shaped portion of much less 20 diameter than the outer part to provide a wide space between said parts and having in the inner end of said cup-shaped portion a threaded opening for the reception of a spark plug and an interlocking joint connection between said parts whereby when assembled and connected they form a unitary structure. 25

In testimony that I claim the foregoing as my invention, I have signed my name.

CHARLES SCHAEFFER.
